UNITED STATES PATENT OFFICE.

SIGVALD JOHANNESSON, OF NEWARK, NEW JERSEY.

TUNNEL LINING.

Application filed November 12, 1926. Serial No. 147,925.

This invention relates to tunnel linings and has for its object the provision of certain improvements in concrete tunnel linings. More particularly, the invention contemplates an improved precast concrete block for tunnel lining, and an improved tunnel lining built up primarily of precast concrete blocks.

The tunnel lining of the invention may be circular or may have any other suitable cross section. The lining is built up of annular units conforming in configuration to the cross section of the tunnel lining. Each annular unit consists of a plurality of precast concrete blocks which may, if desired, be reinforced with steel or the like. Two or more metallic tubes are inserted in each concrete block in such manner that they are parallel to the axis of the tunnel. These tubes serve the two-fold purpose of forming a means of taking the reaction from the shield jacks (when the shield method is used), and of providing a means of connecting the concrete blocks to the annular unit of the lining previously erected. The details of this connection may vary, but I have herein described and illustrated what I now consider the preferred method of connection.

In its preferred form, the precast concrete block has a length, measured circumferentially around the lining, which is more than twice as great as its width, measured in the direction of the axis of the tunnel. Each concrete block is preferably provided with one or more pipes extending from the outside of the lining into the tunnel and tapped with a screw thread. The purpose of these pipes is to relieve any water pressure on the inner lining of cement mortar during the period of setting. These pipes may also be used for grouting outside of the lining.

The precast concrete blocks are so assembled that the tubes in adjacent blocks register with one another. In other words, the ends of the tubes in one block are in contact with the ends of the tubes in the adjoining or next adjacent blocks. The faces of the concrete blocks are in contact with the faces of the adjoining blocks. In the preferred form of the invention the inner edges of each block are beveled or cut back so as to form, when the blocks are assembled, a groove all around the inner perimeter of each block. When erected or assembled, the longitudinal joints of each annular unit are staggered with respect to

the longitudinal joints of each adjacent or adjoining unit.

When one or more complete annular units of concrete blocks have been erected or assembled, a metallic reinforcement is attached to the inner surface of the assembled blocks and a coating of cement mortar is applied over the entire inner surface of the assembled blocks and extending into and filling the grooves between adjoining blocks. The cement mortar is preferably blown on by pressure from a cement gun and may conveniently be the so-called "Gunite" lining.

The foregoing and other novel features of the invention will be better understood from the following description taken in conjunction with the accompanying drawings in which I have illustrated what I now consider the preferred mode of practicing the invention. In the drawings

Fig. 1 is a cross section (on the section line 1—1 of Fig. 2) of a circular tunnel lining embodying the invention.

Fig. 2 is a sectional elevation of the lining taken on the section line 2—2 of Fig. 1.

Fig. 3 (a cross section on the line 3—3 of Fig. 4) illustrates my preferred way of connecting adjacent annular units of the precast concrete blocks.

Fig. 4 is a detail end view, partly in section of the improved lining.

Fig. 5 is an inside elevation of a precast concrete block of the invention.

Figs. 6 and 7 are sectional views taken on the section lines 6—6 and 7—7 respectively of Fig. 5.

The tunnel lining of the invention, in its complete and preferred form, comprises an outer primary lining built up of precast concrete blocks 10 and an inner lining of cement mortar 11 covering the entire inner surface of the primary lining. The precast concrete blocks are at least twice as long as they are wide. In other words, each block has a length, measured circumferentially around the lining which is more than twice as great as its width, measured in the direction of the axis of the tunnel.

The inner edges of each concrete block 10 are beveled (12) or cut back so as to form grooves 13 around the inner perimeter of each block when the blocks are assembled. A plurality of spaced metallic tubes 14 are embedded in each concrete block. These tubes may be of cast iron, steel, or other appropriate metal and are arranged sub-

stantially parallel to the axis of the tunnel, when the blocks are assembled. Each tube 14 has a threaded opening 15 near each end thereof and towards the inside of the block and registering with openings 16 in the block.

In assembling the precast concrete blocks 10, dowel pins 17, preferably steel pins, are inserted in one end of the tubes 14. The 16 dowel pins are secured in position in the tubes by set screws 18. The dowel pins have two spaced conical depressions 19 and 20 in which the conical ends of the set screws fit. The conical depression 20 is slightly larger 15 than the conical depression 19 so as to provide some flexibility and insure proper seating of the set screws. The dowel pins 17 extend from the face of each block 10 gradually varying distances, so as to facilitate 20 assembling of the blocks. Thus, in the assembled lining of concrete blocks, one end of each dowel pin will be in slightly staggered relation with the corresponding ends of each of the circumferentially adjacent pins. 25 This permits the concrete block being assembled in position to be successively caught by the dowel pins.

The tunnel lining illustrated in the accompanying drawings is circular in cross 30 section and the precast concrete blocks are sector-shaped. Each annular unit of the outer primary lining consists of eight individual concrete blocks. For purposes of illustration the tunnel lining may be considered as approximately fifteen feet in internal diameter. The circumferential length 35 of the precast concrete blocks will be about six feet, and the width of the blocks (measured in the direction of the tunnel axis) may conveniently be approximately one foot. The blocks may be of any appropriate depth 40 or thickness, and in the specific example here given, this dimension may conveniently be about one foot.

45 The concrete blocks 10 are so assembled that the longitudinal joints of adjacent annular units are staggered (see Fig. 2). By this arrangement, the individual blocks in each annular unit are fastened together and, 50 with the arrangement of dowel pins described and illustrated, all of the cement blocks are united in a substantially unitary structure.

When the outer primary winding of pre- 55 cast concrete blocks has been erected to a desired extent, a metallic reinforcement 21 is attached to the inside surface of this lining. This metallic reinforcement may conveniently consist of wire cloth, say two to four 60 inches mesh, or steel wire, say No. 12 gauge, tied or otherwise appropriately fastened to the heads of the set screws 18. A layer of cement mortar 11 of appropriate thickness, say about two inches, is then applied to the 65 inner surface of the primary lining. The

cement mortar is blown on by pressure from a cement gun, and may advantageously be a "Gunite" lining. The lining of cement mortar fills the grooves 13 and covers the entire inner surface of the primary lining to a 70 depth of the desired thickness.

I prefer to provide each precast concrete block with one or more pipes 22 extending from the outside to the inside of the block. The inner ends of these pipes are preferably 75 threaded to permit the coupling thereto of grouting means.

The improved lining of the invention is generally adapted for tunnels of all types. In particular, the lining of the invention is 80 suitable for transportation tunnels such as railway, highway, sewage, and water tunnels, as well as for tunnels for public utility pipes and the like.

The improved tunnel lining of the invention possesses numerous features of novelty and advantage both with respect to its ultimate structure and with respect to its erection. Thus, the novel shape of the precast concrete blocks, that is, relatively long and 85 relatively narrow, makes it possible to erect the outer primary winding quickly, safely and in true shape. The lining is capable of resisting bending stresses set up by pressure of the adjoining soil, thus making it possible to decrease the thickness of the lining as compared with the heretofore usual types 90 of concrete block linings, which are capable of resisting only direct compression stresses. The inner lining of cement mortar applied under pressure and extending into the grooves between the concrete blocks forms a most effective water-proofing means for the primary lining of precast concrete blocks. The pipes extending through the precast 95 concrete blocks form an efficient means of relieving the water pressure when present, so as to permit a proper setting of the cement mortar applied under pressure from a cement gun. The method of connecting 100 the concrete blocks is simple in operation, thereby ensuring rapid erection, and is very effective in uniting the blocks in a substantially unitary structure.

I claim:

1. A sector-shaped precast concrete block for tunnel lining having at least part of its inside edges beveled, a plurality of metallic tubes embedded in the block, certain of said tubes extending axially with respect to the tunnel axis, and at least one of said tubes extending radially with respect to the tunnel axis, each of said tubes having a threaded opening.

2. A sector-shaped precast concrete block 125 for tunnel lining having a circumferential length greater than twice the width of the block and having at least part of its inside edges beveled, a plurality of metallic tubes embedded in the block and certain of said 130

tubes extending axially with respect to the tunnel axis, and at last one of said tubes extending radially with respect to the tunnel axis, each of said tubes having a threaded opening toward the inside of the block.

3. A sector-shaped precast concrete block for tunnel lining having a circumferential length greater than twice the width of the block and having at least part of its inside edges beveled, and a plurality of spaced metallic tubes embedded in said block, each of said tubes having a threaded opening near each end thereof registering with openings on the inside of the block.

4. A tunnel lining built up of precast concrete blocks, each of said blocks having a plurality of spaced metallic tubes embedded therein and extending substantially parallel to the axis of the tunnel, said blocks being so assembled that the tubes in adjacent blocks register with one another, dowel pins mounted in the registering tubes, and set screws for securing the dowel pins in the tubes.

5. A tunnel lining built up of precast concrete blocks, each of said blocks having a plurality of spaced metallic tubes embedded therein and extending substantially parallel to the axis of the tunnel, each of said tubes having a threaded opening towards the inside of the block, said blocks being so assembled that the tubes in adjacent blocks register with one another, dowel pins mounted in the registering tubes, and set screws cooperating with said threaded openings for securing the dowel pins in the tubes, said dowel pins having conical depressions in which the ends of said set screws fit.

6. A tunnel lining of circular configuration built up of sector-shaped precast concrete blocks, each of said blocks having a plurality of spaced metallic tubes embedded therein and extending substantially parallel to the axis of the tunnel, each of said tubes having a threaded opening near each end thereof and towards the inside of the block, said blocks being so assembled that the tubes in adjacent blocks register with one another, dowel pins mounted in the registering tubes, and set screws cooperating with said threaded openings for securing the dowel pins in the tubes.

7. A tunnel lining comprising an outer primary lining built up of precast concrete blocks which have a length greater than twice the width of the block, each of said blocks having at least part of its inside edges beveled thereby forming grooves in the inner surface of the assembled blocks, an inner lining of cement mortar filling said grooves and covering the inner surface of said primary lining, and a metallic reinforcement interposed between said linings and secured to the primary lining.

8. A tunnel lining of circular configuration comprising an outer primary lining

built up of sector-shaped precast concrete blocks, each of said blocks having at least part of its inside edges beveled thereby forming grooves in the inner surface of the assembled blocks, an inner lining of cement mortar filling said grooves and covering the inner surface of said primary lining, and a metallic reinforcement interposed between said linings.

9. A tunnel lining of circular configuration comprising an outer primary lining built up of sector-shaped precast concrete blocks which have a length greater than twice the width of the block, each of said blocks having at least part of its inside edges beveled thereby forming grooves in the inner surface of the assembled blocks, an inner lining of cement mortar filling said grooves and covering the inner surface of said primary lining, and a metallic reinforcement interposed between said linings.

10. A tunnel lining comprising an outer primary lining built up of precast concrete blocks, each of said blocks having a plurality of spaced metallic tubes embedded therein and extending substantially parallel to the axis of the tunnel, said blocks being so assembled that the tubes in adjacent blocks register with one another, dowel pins mounted in the registering tubes, set screws for securing the dowel pins in the tubes, an inner lining of cement mortar covering the inner surface of said primary lining, and a metallic reinforcement interposed between said linings and secured to said set screws.

11. A tunnel lining comprising an outer primary lining built up of precast concrete blocks which have a greater length than twice the width of the block, each of said blocks having a plurality of spaced metallic tubes embedded therein and extending substantially parallel to the axis of the tunnel, said blocks being so assembled that the tubes in adjacent blocks register with one another, each of said blocks also having at least part of its inside edges beveled thereby forming grooves in the inner surface of the assembled blocks, dowel pins mounted in the registering tubes, and an inner lining of cement mortar filling said grooves and covering the inner surface of said primary lining.

12. A tunnel lining comprising an outer primary lining built up of precast concrete blocks which have a greater length than twice the width of the block, each of said blocks having a plurality of spaced metallic tubes embedded therein and extending substantially parallel to the axis of the tunnel, each of said tubes having a threaded opening towards the inside of the block, said blocks being so assembled that the tubes in adjacent blocks register with one another, dowel pins mounted in the registering tubes,

set screws cooperating with said threaded openings for securing the dowel pins in the tubes, an inner lining of cement mortar covering the inner surface of said primary lining, and a metallic reinforcement interposed between said linings and secured to said set screws.

13. A tunnel lining built up of precast concrete blocks which have a length greater than twice the width of the block, each of said blocks having a plurality of spaced metallic tubes embedded therein and extending substantially parallel to the axis of the tunnel, said blocks being so assembled that the tubes in adjacent blocks register with one another, and dowel pins mounted in the registering tubes with one end of each of said pins in staggered relation with the corresponding ends of each of the circumferentially adjacent pins.

14. A tunnel lining comprising an outer primary lining built up of precast concrete blocks which have a greater length than twice the width of the block, each of said blocks having a plurality of spaced metallic tubes embedded therein and extending substantially parallel to the axis of the tunnel, each of said tubes having a threaded opening towards the inside of the block, said blocks being so assembled that the tubes in adjacent blocks register with one another, each of said blocks also having at least part of its inside edges beveled thereby forming grooves in the inner surface of the assembled blocks, dowel pins mounted in the registering tubes, set screws cooperating with said threaded openings for securing the dowel pins in the tubes, an inner lining of cement mortar filling said grooves and covering the inner surface of said primary lining, and a metallic reinforcement interposed between said linings and secured to said set screws.

15. A tunnel lining of circular configuration comprising an outer primary lining built up of sector-shaped precast concrete blocks which have a greater length than

twice the width of the block, each of said blocks having a plurality of spaced metallic tubes embedded therein and extending substantially parallel to the axis of the tunnel, each of said tubes having a threaded opening near each end thereof and towards the inside of the block, said blocks being so assembled that the tubes in adjacent blocks register with one another, each of said blocks also having at least part of its inside edges beveled thereby forming grooves in the inner surface of the assembled blocks, dowel pins mounted in the registering tubes with one end of each of said pins in staggered relation with the corresponding ends of each of the circumferentially adjacent pins, set screws cooperating with said threaded openings for securing the dowel pins in the tubes, an inner lining of cement mortar filling said grooves and covering the inner surface of said primary lining, and a metallic reinforcement interposed between said linings and secured to said set screws.

16. A tunnel lining comprising an outer primary lining built up of pre-cast blocks, each of said blocks having a plurality of spaced metallic tubes embedded therein and extending substantially parallel to the axis of the tunnel, said blocks being so assembled that the tubes in adjacent blocks register with one another, dowel pins mounted in the registering tubes, and means in adjacent blocks for fastening each dowel pin in place.

17. A surface covering comprising interlocking pre-cast elements, each of said elements having spaced tubes therein adapted to register when the elements are assembled, dowel pins mounted in the registering tubes of adjacent blocks, and means in each adjacent block for fastening each dowel pin in position to lock said adjacent blocks together.

In testimony whereof I affix my signature.

SIGVALD JOHANNESSON
